UNITED STATES PATENT OFFICE.

OTIS A. MYGATT, OF NEW YORK, N. Y.

DESIGN FOR A SHADE OR REFLECTOR.

46,004.

Specification for Design. Patented June 23, 1914.

Application filed July 1, 1909. Serial No. 505,508. Term of patent 14 years.

To all whom it may concern:

Be it known that I, OTIS A. MYGATT, residing at New York, in the county of New York and State of New York, have invented and produced a certain new, original, and ornamental Design for a Shade or Reflector, of which the following is a specification, reference being had therein to the accompanying drawings.

Figure 1 of the drawing is a plan view of a shade or reflector embodying my design, and Fig. 2 is an elevation of the same.

My design is for a shade or reflector com-

posed of glass and consists in the application to the outside of the said shade or reflector of a series of longitudinally extending prisms, the said prisms being interrupted so as to produce wave-like lines extending around the shade or reflector.

I claim—

The ornamental design for a shade or reflector substantially as shown and described.

OTIS A. MYGATT.
